UNITED STATES PATENT OFFICE.

FRANK GUY, OF SPRINGFIELD, ILLINOIS.

ACETYLENE-LAMP.

1,237,637.

Specification of Letters Patent. Patented Aug. 21, 1917.

Application filed October 15, 1915. Serial No. 56,044.

To all whom it may concern:

Be it known that I, FRANK GUY, a citizen of the United States, residing at Springfield, in the county of Sangamon and State of Illinois, have invented a new and useful Acetylene-Lamp, of which the following is a specification.

The invention relates to lamps of the type which comprise a horizontally disposed carbide box and a horizontally disposed water reservoir having gas-tight connection with the carbide box, and which employ distributors or sheets of fibrous material adapted to diffuse moisture on substantially the entire area of one end of the mass of carbide in the carbide box.

The present invention is a modification and improvement of the invention set forth in my application, S. N. 780,274, acetylene lamp, filed July 21, 1913.

The purposes of the invention are: to provide simple and effective means adapted to keep the distributors in place in the carbide box and adapted to prevent the drying out of that part of the distributing disks which is not in contact with the mass of carbide in the box; to increase the capacity of the gas chamber of the lamp; to provide means adapted to prevent extinguishing of the flame by the concussions of shot-firing and to provide in conjunction with a burner tube located above the highest attainable level of the spent carbide in the carbide box and equipped with filaments, means adapted to supply dry gas to the burner tube and thereby avoid moistening the filaments.

The invention is illustrated in the annexed drawing to which reference is hereby made, and will be hereinafter particularly described, and the novel features thereof will be finally recited in the claims.

Figures 1 and 2 are respectively a rear elevation and a right-hand end elevation of a lamp embodying the invention.

Fig. 3 is a vertical transverse section on the line X. X. of Fig. 1.

Fig. 4 is a vertical longitudinal section on the line Y. Y. of Fig. 2, and Fig. 5 is a rear elevation of the disk-holder.

Similar reference numerals designate the same parts in the different views.

The lamp body 1 is a cylindrical shell of any suitable sheet metal.

A transverse partition 2 separates the wa-

ter reservoir 3 from the carbide box 8. An opening 4 in the partition 2 intercommunicates between the interior of the reservoir 3 and the carbide box 8.

The shell 1 has screw threads 24.

The cap 12 has screw threads 25 adapted to engage on the screw threads 24.

A gasket 13 surrounds the shell and the cap screws down on the gasket to form a gas tight connection of the cap with the shell.

A short pipe 21 is rigid on the shell 1 and water may be poured through the pipe into the reservoir.

A cap 22 has a hinge connection with the pipe and is fitted in its upper end. The cap 22 has vents 23 through which any gas entering the reservoir may escape to the atmosphere.

The dome 14 is rigid on and extends upwardly beyond the periphery of the shell and the axis of the dome is preferably at right angles to the axis of the shell. The interior of the dome and the interior of that part of the carbide box which is above the carbide 10, together constitute a gas chamber B of greater capacity than is usual in lamps of the type to which this invention relates. The dome 14 being above the chamber 8, the moist carbide will not enter the dome and will not moisten the gas in the dome. The practical advantage of this construction is that the gas chamber of enlarged capacity admits of accumulating an unusually large volume of gas in the chamber, which serves to maintain even pressure in the burner tube, notwithstanding any usual inequalities in the generation of the gas.

A fibrous disk, or a series of parallel fibrous disks 5, preferably of blotting paper, may be connected with the plate 6 as hereinafter described and are adapted to absorb water from the reservoir and diffuse it on the end wall of the mass of carbide.

The disk holder consists of a circular thin and flexible metal plate 6, having an opening 9 of a height somewhat greater than the depth of the usual charge of the carbide 10. The plate 6 has integral fingers 27 adapted to be bent to bear against the fibrous disks to connect them with the plate. If the disks become clogged and it be desired to remove them and substitute clean disks, the fingers may be pried away from the disks, the clogged disks may be removed, fresh disks

may be placed on the plate and the fingers may be again pressed against the disks to hold them on the plate, and this procedure will be repeated each time that it is desired 5 to change the disks. The plate 6 serves to cover and protect the disks.

In practice it has been found that if unprotected disks of the same diameter as the inside of the carbide box be used in contact 10 with substantially the entire area of the end wall of the mass of carbide the heat of the gas in the carbide box will dry out that part of the disks which is above the carbide and cause dry spots through which gas from the 15 carbide box may pass through the disks, downward along the face of the partition 2 and through the opening 4 into the reservoir 3 and thence to the atmosphere, resulting in waste of gas. The plate 6 prevents 20 the drying out of the disks and the consequent waste of gas.

A circular spring 7 has handles 26 for manipulating the spring. When the disk-holder is in place in the shell the spring will 25 be inserted in the box 8 and will be pressed against the plate 6 to keep it in place.

A hook 19 rigidly connected with the shell 1 is adapted to serve as a handle for the lamp and may also be used to support the 30 lamp on the cap or clothing of the user.

A sleeve 15 is stationary on and radial with respect to the dome and extends inwardly to about the center of the dome.

The burner tube 16 is fitted to the interior 35 of the sleeve so that when the tube is pushed into the sleeve it will be in gas tight connection with the sleeve. The burner tip 17 is fitted in the usual manner in the outer end of the tube. The reflector 18 is connected 40 with the tube 16 by a set screw 28.

The sleeve 15 supports the burner tube 16 in a horizontal position so that the flame at the burner tip will be projected horizontally forward, and so that the back of the reflector mounted on the burner tube may lie close to the periphery of the shell, thus contributing to the compactness and perfect balance of the lamp as a whole. The burner and the reflector being above and close to 50 the lamp body it protects them from accidental injury.

In practice it is found that the horizontally projected flame is much superior to a vertically projected flame because the horizontal flame does not produce the rising and falling shadows which result from the fluctuations of a vertically projected flame and which are very annoying and confusing to the user of the lamp.

55 Filaments 20, preferably of jute, occupy the interior of the tube and control the flow of gas through the tube. The friction of gas on the filaments 20 prevents the gas from going so far inward as to admit of 60 extinguishing the flame by the concussions

of shot-firing. If the gas pressure in the chamber B is strong, a sufficient number of filaments will be used to obstruct the tube sufficiently to prevent the gas from flowing too rapidly through the tube and blowing 70 out through the burner tip and extinguishing the flame. If there is less gas pressure in the chamber B a less number of filaments will be used in the tube, so that the flow of the gas through the tube may not be unduly 75 obstructed. In addition to controlling the outflow of gas through the tube, the filaments serve to prevent inflow of gas under the concussions of shot firing. In other words, the filaments prevent excessive outward flow and consequent wasting of gas, and also prevent such sudden inward flow of the gas as to cause the extinguishing of the flame by the concussions of shot firing. The aggregated filaments serve as a filter 80 and pressure controller for the outwardly flowing gas and serve in conjunction with the gas occupying the interstices between the filaments to form a gas cushion effective to prevent such rapid inflow of gas as would 85 cause the extinguishing of the flame.

In practical use a disk or disks will be placed in the holder 6 and it will be placed in the carbide box in close contact with the partition 2, and the spring 7 will be pressed 90 against the holder to keep it in place; a suitable charge of carbide will be put in the box 8 and the cap 12 will be screwed down onto the gasket to make a gas tight connection of the cap with the shell; such number of filaments 20 as are deemed sufficient 95 will be placed in the tube 16, and the burner tip will be placed in the outer end of the tube; a sufficient quantity of water will be poured through the pipe 21 into the reservoir 3 and the cap 22 will be pressed into the end of the tube; the water will seep 100 through the disk, or disks, and will be diffused on the end wall of the mass of carbide and the generating of gas will begin. If the generation of gas is too slow, a disk or disks will be removed to permit more rapid distribution of the water; or if the generation 105 of gas is too rapid, a disk or disks will be added to retard the distribution of the water and thus diminish the generating of gas. The blotting paper disks 4 give quick and even distribution of water and are not easily injured or destroyed by the carbide; water in contact with one disk is readily diffused 110 through all the disks contained in the holder and is uniformly applied over substantially 115 the entire area of the end wall of the mass of carbide.

The associated disks constitute a barrier 120 between the water in the reservoir 3 and the gas in the chamber 8 and the adding of a disk or disks will augment the barrier to an extent sufficient to cause increased gas pressure in the chamber and when the augmented 125

barrier is saturated it will more strongly oppose the passage of gas through the barrier, with the result that while the gas pressure in the chamber is increased, said increased pressure is effectively opposed by the augmented and saturated barrier so that gas will not be forced back through the water in the reservoir.

If the pressure in the chamber B is so great as to cause the gas to blow out through the burner tip and extinguish the flame, the tube 16 will be withdrawn and a sufficient number of additional filaments 20 will be placed in the tube, and the tube will be replaced in the sleeve. If the pressure in the chamber B is found insufficient to force the gas outward through tube, a sufficient number of filaments will be removed to permit proper outflow of gas through the tube. When the diffusion of water through the disk or disks is properly controlled, as described, and the proper number of fibers are in place in the tube 16 the flow of gas in the tube will be practically uniform and if a shot be fired the fibers will oppose pulsation of the gas and prevent the extinguishing of the flame.

If gas blows out through the vents 23 when there is proper pressure at the burner tip, the mass of disks 4 may be increased sufficiently to stop the backward flow of gas into the reservoir 3. It will be seen that the filaments 20 and the saturated disks 4 co-act to control the gas pressure at the burner tip and to avoid the waste of gas through the vents 23.

Having fully described my invention, what

I claim as new and desire to secure by Letters Patent is:

1. In an acetylene generator, the combination of a reservoir; a box adapted to contain carbid; a diaphragm between the reservoir and the box and having an opening intercommunicating between the reservoir and the box; a plate within the box and having an opening adjacent to and larger than the opening in the diaphragm and also having flexible fingers; a body of absorbent material of substantially the same contour as said plate and adapted to be engaged by the fingers thereof to keep the body of absorbent material in place on the plate; and means for detachably connecting the plate with the box.

2. In an acetylene generator, the combination of a reservoir; a box adapted to contain carbid; a diaphragm between the reservoir and the box and having an opening intercommunicating between the reservoir and the box; a plate within the box and having an opening adjacent to and larger than the opening in the diaphragm; a body of absorbent material connected with the plate and covering the opening thereof; and a spring adapted to hold the plate in the box with one face of the body of absorbent material against one face of the diaphragm.

In witness whereof I have hereunto signed my name at Springfield, Illinois, this 13th day of October, 1915.

FRANK GUY.
